UNITED STATES PATENT OFFICE.

WILBUR M. STONE, OF NEW YORK, N. Y., ASSIGNOR TO OXFORD LINEN MILLS, A CORPORATION OF MAINE.

DESIGN FOR A FIBROUS SHEET MATERIAL FOR SURGICAL DRESSINGS.

No. 40,046.

Specification for Design.

Patented June 8, 1909.

Application filed September 1, 1908. Serial No. 451,265. Term of patent 14 years.

To all whom it may concern:

Be it known that I, WILBUR M. STONE, a citizen of the United States, residing at New York, in the county and State of New York, have invented a new, original, and ornamental Design for Fibrous Sheet Material for Surgical Dressings, of which the following is a specification, reference being had to the accompanying drawing, forming part thereof.

The figure is a plan view of a fibrous sheet material for surgical dressings showing my new design.

I claim:

The ornamental design for fibrous sheet material for surgical dressings, as shown.

WILBUR M. STONE.
